DESIGN FOR A MATTRESS COVER OR SIMILAR ARTICLE

Ruth Sawyer Foggett, New London, Conn., assignee to The Palmer Brothers Company, New London, Conn., a corporation of Connecticut

Application March 9, 1939, Serial No. 83,485

Term of patent 7 years

To all whom it may concern:

Be it known that I, Ruth Sawyer Foggett, a citizen of the United States, residing at 234 Connecticut Avenue, city and county of New London, State of Connecticut, have invented a new, original, and ornamental Design for a Mattress Cover or Similar Article, of which the following is a specification, reference being had to the accompanying drawing, forming part thereof.

The figure of the drawing shows one-fourth of the design, the other three complementary sections being of the same ornamentation, and being arranged in proper relation to complete the rectangle.

I claim:

The ornamental design for a mattress cover or similar article, as shown and described.

RUTH SAWYER FOGGETT.
